K. KOHN

TOY TORPEDO

Filed Oct. 6, 1926

FIG. 1.

FIG. 2.

FIG. 3.

Inventor

Koby Kohn,

By Watson, Cott, Morse & Grindle,

Attorney

UNITED STATES PATENT OFFICE.

KOBY KOHN, OF NEW YORK, N. Y.

TOY TORPEDO.

Application filed October 6, 1926. Serial No. 139,923.

This invention relates to fireworks and more particularly to that class of fireworks known as a toy torpedo which comprises a container for an explosive compound and some means for initiating the explosion of the compound when the torpedo receives a violent impact, such as upon striking a hard object, after having been thrown.

More particularly it is an object of this invention to provide a toy torpedo which shall be safe to manufacture, store, ship and handle.

A still further object of the invention consists in the provision of a toy torpedo, in which the explosive compound is confined in a casing or container and the abrasive particles which are used to ignite the explosive are secured to some object which is normally stationary but will be moved into contact with a surface so as to abrade the explosive material between the two when a violent impact is given to the torpedo.

A still further object of the invention consists in the provision of a torpedo having a completely enveloping container, partially filled with a loose explosive compound and having, projecting inwardly into the explosive chamber, a bendable member, said member and a wall of the container having abrasive surfaces adapted to be brought together to ignite the explosive compound upon impact of the torpedo.

The above and other objects of the invention will be more apparent, to those skilled in the art, after a consideration of the following specification and accompanying drawings, wherein are disclosed, by way of example only, a single embodiment of the invention, with the understanding, however, that various changes may be made therein without departing from the spirit of the invention or the scope of the appended claims.

In said drawings:

Figure 1 is a perspective view of one form of torpedo constructed according to the present invention;

Figure 2 is a central longitudinal section through such a torpedo; and

Figure 3 is a transverse section on line 50 3—3 of Fig. 2.

Toy torpedoes, as usually made, comprise a more or less rigid container completely enclosing a compartment in which is arranged a powdered explosive composition. Small granules or particles of gravel or similar abrasive material of sufficient size to have

considerable weight and momentum are mixed with the explosive, so that when the torpedo receives a violent impact, the particles of gravel abrade against each other and ignite the explosive. This type of torpedo is unsafe to manufacture and to handle during shipping and storing, for the loose particles of gravel may so rub against each other, due to slight jars incident to handling, as to cause the explosive to ignite. The ignition of a single torpedo in a case will cause the explosion of the whole case and may result in large property damage and even loss of life. The present torpedo, while following the style of the torpedo just described, insures safety, except upon intentional impact to explode the torpedo, by securing all of the abrasive material to portions of the container which are relatively stationary and spaced apart, except at the time of the intentional and violent impact, when they move toward each other and cause the abrasive to ignite the explosive material.

Referring to the drawings, it will be seen that for the sake of convenience and simplicity a tube type of torpedo has been disclosed. The main body of the container is formed from a cylindrical tube 10 made of paper, cardboard or any material which is not brittle and which will only bend and not break upon impact. The tube is adapted to be closed at its ends by the caps 11 and 12, which are formed to telescope over the tube and be secured thereto in any suitable manner, such as by an adhesive. Obviously the caps may fit within the tube or may even be only disks secured in the ends of the tube, their sole function being to retain the explosive material in the tube and to offer a material resistance to the expanding gases resulting from the explosion so as to cause a loud report. To further increase the resistance of the complete container to the expanding gases it may be covered with a gastight and preferably waterproof covering 13. This may take the form of suitably impregnated paper wrapped around the torpedo, or it may be a glue or other plastic or mastic material which is applied to the container in a heated or diluted condition, after the torpedo has been completed, and allowed to dry or harden on the surface.

The cap 11 as shown has a flat circular outer end and is preferably formed from paper, pasteboard or the like. The cap 12, however, is provided with an inturned tubu-

lar boss or portion 14, preferably integral with the cap and having the hole 15 therein near the center of the cap and thus substantially concentric with the tube 10.

- 5 A suitable member 16 is inserted in the hole 15 and secured therein by adhesive material or merely by the friction of engagement. This member 16 is made of some such material as rolled up paper, or the like, whereby it is more or less resilient, flexible or bendable. It has sufficient weight and projects far enough beyond the supporting boss 14 so that when the torpedo is thrown and strikes against a hard surface, the end 10 of the member 16, due to its momentum, will move into engagement with the inner surface of the wall of the tube 10.

In the manufacture of the torpedo the member 16 is preferably first applied and secured to a cup 12 which is then properly attached to the tube 10. The inner surface of the wall of the tube 10 and the outer surface of the member 16 are then coated with a suitable adhesive 20, such as shellac, glue 25 or the like, and the space between the tube and the member is filled with a suitable abrasive material such as graded sand, powdered glass, emery or the like. When the adhesive has properly set or hardened, the excess abrasive material is poured out, leaving a coating of abrasive particles 17 on the inside of the wall of the tube 10 and a similar coating 18 on the outer surface of the bendable member 16. Instead of an adhesive material such as glue, the above mentioned surfaces may be coated with pitch or the like and heated abrasive material poured in. Upon cooling, the excess material is poured out and that remaining sticks to the pitch by reason of its having melted into the 30 surface thereof.

Explosive composition 19 is next poured into the space between the two abrasive walls. Such material may comprise an intimate 45 mechanical mixture of powdered chlorate of potash, powdered sulfur and powdered antimony, or any similar mixture which will explode upon abrasion and which is suitable for use in toy torpedoes. The material 50 does not completely fill the container, in order that the member 16 may have room to move when the torpedo is subjected to impact. The cap 11 is next affixed to the tube and the outer coating 13 applied if this 55 is desired. Upon drying, the torpedo is complete.

It will be obvious that the normal position of the bendable member 16 is in the center of the tube. The coating of adhesive 60 makes this member more or less resilient and it maintains its position. The coating of adhesive adds weight to the member. When the torpedo is thrown and suddenly comes into contact with a hard surface, the momentum of the member 16 causes it to con-

65 tinue to move until the abrasive on its surface engages with the abrasive on the inside of the tube and ignites any particles of explosive composition which may be between these two abrasive surfaces, and thus initiates the explosion. It may also be found 70 that the impact causes the wall of the tube to be pressed inwardly where it strikes a hard surface, and thus assists in bringing the two abrasive surfaces together. It will 75 be found that regardless of the position in which the torpedo strikes, the two abrasive surfaces will come together and initiate the explosion.

While for the sake of convenience a tube 80 type of torpedo has been shown, it will be obvious that various other of the common forms, such as the globe torpedo, may be constructed according to this invention, and the claims are therefore not to be construed 85 as limited by the drawing.

Having thus described the invention, what is claimed as new and desired to be secured by Letters Patent is:

1. In a toy torpedo, in combination, a 90 closed container, an explosive loosely arranged in said container, a resilient member projecting from the inner surface of a wall of the container, said member being adapted to cooperate with the inner surface of a wall 95 to explode said explosive when the torpedo receives a violent impact.

2. A container for explosive for a toy torpedo having a resilient member projecting from the inner surface of one of the walls. 100

3. A container for explosive, for a toy torpedo, having walls, the inner surface of one of which is coated with abrasive, and a resilient member projecting from one of said walls into the compartment defined thereby. 105

4. A container for explosive for a toy torpedo, having walls, the inner surface of one of which is coated with abrasive, a flexible member projecting from one of said walls into the container, said member being provided with an abrasive surface. 110

5. A container for explosive, for a toy torpedo, having enveloping walls defining a compartment for explosive, means projecting from one of said walls into said compartment, said means being bendable, there being an abrasive surface on said means. 115

6. A toy torpedo including a container enclosing an explosive, and a bendable member projecting into said container and adapted to cooperate with the inner surface of a wall thereof to explode the explosive when the torpedo is subjected to a violent impact. 120

7. In a toy torpedo, in combination, a paper tube open at the ends, a cap secured to one end of said tube, a bendable member passing through said cap, secured therein and projecting into said tube, abrasive on the inner walls of said tube and on said member, explosive composition between said 125 130

abrasive surfaces, a cap on the other end of said tube and a gastight covering over said tube and caps.

8. In a toy torpedo, in combination, a tube open at the ends, closures for said ends forming a compartment within the tube, explosive material in said compartment, and a member projecting into said compartment, said member being arranged substantially centrally of the tube.

9. In a toy torpedo, in combination, a tube open at the ends, closures for said ends forming a compartment within the tube, explosive material in said compartment, and a pliable

member projecting into said compartment, 15 said member being arranged substantially centrally of the tube.

10. In a toy torpedo, in combination, a tube open at the ends, closures for said ends forming a compartment within the tube, explosive material in said compartment, and a pliable member projecting into said compartment, said member being arranged substantially centrally of the tube and having an abrasive surface.

In testimony whereof I hereunto affix my signature.

KOBY KOHN.
